LIGHTING FIXTURE

Marcus E. Kanter, Cleveland, Ohio, assignor to
 Railley Corporation, Cleveland, Ohio, a corpora-
 tion of Ohio

Application April 29, 1939, Serial No. 270,883

3 Claims. (Cl. 240—73)

This invention relates to an electrical lighting fixture which is adapted to be detachably supported upon a wall. Lighting fixtures of this character usually include a plaque or bracket which supports a lamp socket adapted to receive an electric lamp bulb therein. Such plaques are usually hung on a wall some distance from the floor and are connected with an electrical outlet generally disposed adjacent the floor. This invention relates primarily to the provision of a wall fixture of the character described which has incorporated therein a device for preventing undue strain being placed upon the terminal connections of the lamp socket or switch which may be associated with the fixture.

One object of the invention is to provide an electrical lighting fixture which includes a wall bracket or sconce which supports the lamp proper and which has secured thereto an anchoring member to which the wires or conductors are secured in such a manner as to prevent undue strain being placed upon the terminal connections of the lamp socket.

A further object of the invention is to provide a lighting fixture which includes a wall bracket or sconce to which is secured an electric lamp socket from which leads conductors or wires which lead through the bracket and are secured to the bracket in such a manner that undue strain will not be placed upon the connections between the lamp socket and the conductor.

A still further object of the invention is to provide an electrical lighting fixture of the character described which comprises a bracket or base which supports a lighting fixture and which is adapted to be detachably supported upon a wall or the like, the bracket having secured thereto and substantially concealed thereby a switch which has a part thereof shaped to receive the conductor therethrough and to be attached to the conductor in such a manner as to prevent undue strain being placed upon the connections between the conductor and switch.

A further object of the invention is to provide an electrical lighting fixture having the above described distinguishing characteristics and features and which is well adapted for production at comparatively low cost.

Further and more limited objects of the invention will appear as the description proceeds and by reference to the accompanying drawing by which Fig. 1 is a view in rear elevation of a lighting fixture; Fig. 2 is a vertical sectional view of the fixture; Fig. 3 is a perspective view of the anchoring member which is secured to the fix-

ture and receives the conductor therethrough; Fig. 4 is a perspective view of a modified form of knot anchoring member; Fig. 5 is a perspective view of a second modified form of anchoring member adapted to have a switch secured thereto; Fig. 6 is a detail sectional view showing a wall sconce having a switch secured thereto and provided with an anchoring member receiving the conductor; Fig. 7 is a view similar to Fig. 6 disclosing another modified form of the invention in which the anchoring member is formed as a part of the switch; and Fig. 8 is a detail perspective view of the anchoring member used in the construction shown in Fig. 7.

Referring now to the drawing, the reference character 1 designates a wall bracket, plaque or sconce which is preferably in the form of a metal plate shaped as shown most clearly in Fig. 2, and which has secured thereto an arm 2 to the upper end of which is secured a lamp socket 3. The arm 2 is somewhat oval in cross section and receives therein a conductor 4 one end of which is connected with the lamp socket 3. The conductor 4 extends through an opening 5 provided in the bracket and thence through an opening or slot 6 provided in the lower end of the bracket and has a plug 7 connected with the lower end thereof which is adapted to be plugged into the outlet 8. Secured to the bracket 1 is an anchoring member 9 which is preferably formed of metal and shaped as shown in Fig. 3, and held in place by a screw 10 having an ornamental head 11. The anchoring member 9 has an opening therein in which is secured a collar or bushing 12 which is formed of suitable insulating material. In order to prevent undue strain being placed upon the connections between the conductor and the socket terminals, the conductor which is in the form of a pair of flexible wires has a knot 13 tied therein and which is disposed immediately above and adjacent the top of the anchoring member 9. It is of course to be understood that the conductor preferably consists of a pair of wires which are insulated from each other and enclosed within a single covering.

In Fig. 6 there is disclosed a slightly modified form of fixture which consists of a plaque or plate 14 of the same general shape as the bracket 1 shown in Figs. 1 and 2 and which has secured thereto a switch S which is held in place by an anchoring member 14, shown in detail in Fig. 8. The anchoring member 14 has a pair of bendable arms 16 and 17 which receive the switch proper therebetween. The anchoring member is also provided with a threaded member or portion 18.

which projects through an opening in the wall of the bracket and is held in place by a nut 19. Disposed between the member 14 and plate 1^a and surrounding the threaded portion 18 is a downwardly extending anchoring member 20, shown in perspective in Fig. 4, and which is L-shaped in section and has an opening therein which receives a fiber collar or sleeve 21. The passing of current through conductors 22 and 23 is controlled by switch S which latter is inserted within the conductor 23, as shown in Fig. 6. These two conductors are brought together below the switch S and tied in a knot, indicated by the reference numeral 26, which knot is disposed immediately above the opening in the collar 21. This knot prevents any great relative movement in a downward direction between the wires 22 and 23 and the lamp bracket and prevents undue strain being placed upon the terminal connection to the switch. The switch is actuated by a push button 27.

In Fig. 7, there is disclosed still another modification of my invention which is identical with the form of the invention illustrated in Fig. 6, except that the knot anchoring member 20^a is formed as a part of the switch anchoring member 14^a, as clearly illustrated in Fig. 5. The member 20^a is also L-shaped in vertical section and has an opening therein which receives a fiber collar 21^a to support the knot 26^a tied in conductors 22^a and 23^a below switch S. The switch anchoring member 14^a has a pair of bendable arms 16^a and 17^a which receive the switch proper therebetween.

It frequently happens that the length of the wires or conductor connecting the lamp with the circuit is longer than is required and a portion thereof remains loose on the floor and should one trip on this loose portion or should a chair or other object be caught therein, the wire or conductor may be pulled loose from the switch terminals or from the lamp socket, if a switch is not used, unless some means were provided to take up this strain. It will be seen that the knot anchoring members hereinbefore described have the conductor or wires secured thereto in such a manner as to prevent any undue strain being placed upon the switch terminals or upon the terminals of the lamp socket. It is also possible to disconnect the plug from the floor outlet by merely pulling on the lamp bracket without holding the conductor as the knot anchoring member takes up this strain. It is, of course, understood that such an anchoring member may be applied to any switch where desired, such as in

a floor or table lamp or other electrical fixture. It will now be clear that I have provided an electrical lighting fixture which will accomplish the objects of the invention as hereinbefore stated. It is, of course, understood that various changes may be made in the details of construction without departing from the spirit of my invention and that the embodiments of the invention herein disclosed are to be considered merely as illustrative and not in a limiting sense as the invention is limited only in accordance with the scope of the appended claims.

Having thus described my invention, what I claim is:

1. An electrical fixture comprising a supporting member adapted to be hung on a wall, an arm carried by said supporting member and projecting outwardly therefrom, an electrical socket carried by said arm, a conductor having one end connected with said lamp socket and leading along said arm and thence through said supporting member and having its opposite end adapted for connection with an electric line, a switch secured to and substantially concealed by said supporting member, an anchoring member secured to said switch and connected with said conductor and a single means securing said switch, anchoring member, arm and supporting member against relative movement.

2. A lighting fixture comprising a plaque adapted to be hung on a wall, an arm extending outwardly from said plaque, a lamp socket carried by said arm, a conductor having one end connected with said lamp socket and extending along said arm and thence through said plaque and having its opposite end secured to a plug for connection with an electric line, an anchoring member carried by said plaque and secured to said conductor and a threaded connection securing said arm and anchoring member against movement with respect to said plaque.

3. A lighting fixture comprising a plaque adapted to be hung on a wall, an arm extending outwardly from said plaque, a lamp socket carried by said arm, a conductor having one end connected with said lamp socket and extending along said arm and thence through said plaque and having its opposite end secured to a plug for connection with an electric line, a switch and anchoring member carried by said plaque and concealed thereby and a threaded connection securing said switch, anchoring member, arm and plaque against relative movement.

MARCUS E. KANTER.
